[57] CLAIM

The ornamental design for a clothes hamper, substantially as shown and described.

DESCRIPTION

FIG. 1 is a front elevational view of a clothes hamper showing my new design;

FIG. 2 is a top plan view thereof;

FIG. 3 is a rear elevational view thereof;

FIG. 4 is a bottom plan view thereof;

FIG. 5 is a right-side elevational view thereof; and

FIG. 6 is a left side, top, and front perspective view thereof.

The wicker pattern which is shown fragmentarily in all views is understood to repeat throughout the indicated areas.
